UNITED STATES PATENT OFFICE

106,124

DESIGN FOR A METALLIC UTILITY BOX

Seeley F. Pratt, Le Roy, N. Y., assignor to Union
Steel Chest Corporation, Le Roy, N. Y., a cor-
poration of New York

Application February 29, 1936, Serial No. 61,418

Term of patent 14 years

To all whom it may concern:

Be it known that I, Seeley F. Pratt, a citizen
of the United States, residing at Le Roy, in the
county of Genesee and State of New York, have
invented a new, original, and ornamental Design
for a Metallic Utility Box, of which the following
is a specification, reference being had to the ac-
companying drawing, forming part thereof.

Figure 1 is a perspective view of a metallic util-
ity box, showing my new design.

Figure 2 is a front elevation, and
Fig. 3 is a side elevation.

I claim:

The ornamental design for a metallic utility
box, as shown.

SEELEY F. PRATT.
